(57) **CLAIM**

The ornamental design for a pump for liquids, as shown and described.

DESCRIPTION

1. Pump for liquids according to a first embodiment; and
2. Pump for liquids according to a second embodiment.

Fig. 1.1: Axonometric view of the pump for liquids according to the first embodiment claimed design;

Fig. 1.2: Front view thereof;

Fig. 1.3: Left view thereof;

Fig. 1.4: Back view thereof;

Fig. 1.5: Right view thereof;

Fig. 1.6: Top view thereof; and

Fig. 1.7: Bottom view thereof.

Fig. 2.1: Axonometric view of the pump for liquids according to the second embodiment of the claimed design;

Fig. 2.2: Front view thereof;

Fig. 2.3: Left view thereof;

Fig. 2.4: Back view thereof;

Fig. 2.5: Right view thereof;

Fig. 2.6: Top view thereof; and

Fig. 2.7: Bottom view thereof.

(Continued)

The portions of the pump for liquids shown in broken lines
form no part of the claimed design.

1 Claim, 14 Drawing Sheets
